UNITED STATES PATENT OFFICE.

SEYMOUR FISHER, OF DURGON, WEST VIRGINIA.

HORSE-TWITCH.

1,096,420.

Specification of Letters Patent. Patented May 12, 1914.

Application filed March 19, 1912, Serial No. 684,752. Renewed October 2, 1913. Serial No. 793,048.

To all whom it may concern:

Be it known that I, SEYMOUR FISHER, a citizen of the United States, residing at Durgon, in the county of Hardy and State 5 of West Virginia, have invented a new and useful Horse-Twitch, of which the following is a specification.

This invention relates to horse twitches or horse holders, and has for its object to provide a device of this character which is adapted to engage the upper lip of a horse in a rapid manner, and which will serve to hold the upper lip of the animal tightly in an effective manner while the horse is receiving medical treatment, or while the horse is being shod.

This invention also contemplates a device of this character which shall be simple, durable, and inexpensive in construction, and 20 which may be used with ease and convenience to engage and contract the upper lip of the animal in order to hold the animal.

With the foregoing and other objects in view, which will be apparent as the invention is better understood, this invention resides in the novel construction and combination of parts hereinafter set forth and claimed, reference being had to the accompanying drawings, wherein similar reference 30 characters indicate similar parts.

Figure 1 is an elevation of the present device as in use. Fig. 2 is a longitudinal section of the device. Fig. 3 is an elevation of another form of the device embodying certain modifications. Figs. 4, 5 and 6 are enlarged sectional views taken on the lines 35 4—4, 5—5 and 6—6 of Fig. 3, respectively.

Referring in detail to the drawings, the numeral 6 designates an elongated frame, 40 preferably of metal or other rigid material, and which has an ear 7 at its upper end, and ear 9 at its lower end, and an ear 8 intermediate the ends thereof, all of the said ears being on the same side, and being preferably 45 integral with the frame. The ear 8 is provided with an opening 18 therethrough, and the ear 9 is provided with a screw threaded opening 19 therethrough, a bar or rod 10 being screwthreaded through the 50 opening 19 and passing loosely through the opening 18, the ear 8 serving to guide the said rod. The lower end of the rod 10 is formed into a crank 14 for conveniently rotating same, and the upper end of the rod 55 is reduced in diameter as designated by the numeral 11. A head 13 is mounted on the

reduced end 11 of the rod 10, and the washer or other member 12 is welded, riveted or otherwise secured on the reduced end 11 over the head 13 to retain the said head in position. It is understood, however, that the head 13 may be secured to the upper end of the rod 10 in any suitable manner. This head 13 is elongated in form and has the openings 20 and 21 adjacent the respective 60 ends thereof.

A cord, rope, or other flexible member 15 has one end, designated 16, secured to the head 13 through the opening 20, and is doubled through an opening 17 in the ear 7 to provide a noose or loop 25, the free end of the said member 15 being passed through the opening 21 in the head 13. A tubular stop 22, separate from the head 13 is 70 slidable on the free end of the flexible member 15 and has an opening or slot 23 in one side with ears 28 projecting from the edges of the said slot, an eccentric or cam 24 being pivoted between the ears 28 by means of a pin 26. This eccentric or cam 80 24 has the face thereof toothed or serrated and is provided with a finger 27 projecting outwardly therefrom. When the eccentric or cam 24 is swung inwardly, the same is adapted to engage and bite the flexible 85 member 15 to retain the stop in position thereon, the eccentric or cam being actuated by means of the finger 27, as will be understood.

When in use, the upper lip of the horse or animal which is to be held, is engaged by the noose or loop 25, the same having been opened or distended previously by screwing the rod upwardly and releasing the stop 22, and when the lip of the animal is engaged 90 by the noose or loop, the same may be tightened by drawing the free end of the flexible member outwardly and then by sliding the stop 22 against the head 13 and locking the stop in position, by swinging the finger 27 95 inwardly, the noose may be given its initial position on the lip of the animal and then by rotating the rod or screw 10, the head 13 may be drawn downwardly or away from the upper end of the frame 6, in which event, 100 the noose or loop may be further tightened in order to tightly grip the lip of the animal, the screw threads of the rod 10 and the crank 14 providing for a great force for contracting the noose or loop about the lip of the 110 animal. In this manner, the lip of the horse or other animal may be rapidly engaged.

when desired or necessary in order to hold the animal quiet when being operated on, this invention being adapted particularly for use in connection with vicious horses, 5 which may be held quite while being operated upon or being shod for the reason that the noose or loop may be made to tightly grip the upper lip of the animal in order to hurt the animal should the same attempt 10 to move. It will be seen that by means of the adjustable stop 22 the noose or loop may be readily given its initial position upon the upper lip of the animal, and that by means of the rod 10 the noose or loop may then be 15 tightly contracted about the lip of the animal in a convenient and efficient manner. By releasing the eccentric or cam 24 from the flexible member 15, the noose or loop 25 may be readily opened in order to permit the 20 lip of the animal to be withdrawn therefrom.

In the form shown in Fig. 3, the lower ear 9' of the frame 6 is provided with a rectangular opening 29 therethrough, the said opening having screw-threads 19' at its outer end and having slideways or guides 37 along the sides thereof. A member 30 is slidably mounted within the opening 29 in the ear 9', the edges of the member 30 working in the slideways or guides 37. This 30 member 30 is provided at its outer end with the screw threads 19" coöperating with the screw threads 19' and at its inner end has a projecting stud or lug 31. The ear 9' is also provided with a socket or recess 33 at 35 the inner end of the opening 29 in which the coiled wire spring 32 seats, the outer end of the said spring contacting with the inner end of the member 30 and embracing the stub or lug 31. A plate 34 is secured to the bottom of the member 30 and projects beyond the outer end of the ear 9' and has a slot or opening 35 therethrough through which the rod 10 passes, the outer end of the plate 34 being bent or deflected upwardly to 40 provide a thumb piece 36, which thumb piece is normally spaced away from the outer end of the ear 9'. The rod 10 passes between the screwthreaded portions 19' and 19" of the ear 9' and the member 30, respectively, and the member 10 may be rotated 45 the same as with the former form, after the noose has been given its initial position, in order to tighten the noose or loop. The noose is given its initial position by pressing 50 the thumb piece 36 inwardly, which causes the member 30 to be slid away from the rod 10, in which event the rod will be free to be moved longitudinally in order to rapidly contract the noose or loop to engage the lip 55 of the animal and then by releasing the thumb piece, the member 30 will be again engaged with the rod 10 to lock same against longitudinal movement unless it is rotated. This adjustment of the rod 10 is adapted to 60 supplant the adjustment of the stop 22 in

order to afford means for rapidly contracting and opening the noose or loop, but it is understood, that either or both of these means may be employed.

This device may not only be used for engaging the upper lip of the horse or other animal, but may be employed for engaging the ear or other parts of the animal and for various purposes, as will be apparent to those skilled in the art. 75

This device is comparatively simple in construction, is durable and is capable of manufacture at a comparatively small cost, and in its use is both convenient and efficient, this device presenting an article of 80 this character which is highly desirable.

It is understood, that this device is susceptible of alterations or deviations in its details within the scope of the appended claims without departing from the spirit of 85 the invention.

Having described the invention what is claimed as new is:

1. A horse twitch comprising a frame, having ears at its ends, a rod mounted on 90 the frame and having a screwthreaded engagement with one ear, a head carried by the said rod, a flexible member connected at one end to the said head and having a noose passed through the other ear with the free 95 end passing through the said head, and a stop adjustably mounted on the free end of the flexible member and adapted to bear against the head mounted on the said rod.

2. A horse twitch comprising a frame having ears at its ends, a rod screwthreaded through one of the ears, a head carried by the said rod, a flexible member having one end attached to the head and having a noose passed through the other ear with the free 100 end passing through the head, and a stop adjustably mounted on the free end of the flexible member. 105

3. A horse twitch comprising an elongated frame having ears at its ends, and an intermediate ear, a rod screw threaded through the lower ear and guided through the intermediate ear and having a crank at its outer end, a head carried by the inner end of the rod, a flexible member having one 110 end attached to the head and having a noose passing through the upper ear with the free end passing through the head, a tubular stop 115 slidably on the free end of the flexible member, and means carried by the stop for engaging the flexible member. 120

4. A horse twitch comprising an elongated frame having ears at its ends and an intermediate ear, a rod screw threaded through the lower ear and guided through the intermediate ear and having a crank at its lower end, a head carried by the upper end of the rod, a flexible member having one end attached to the head and having a noose 125 passed through the upper ear with the free 130

end passing through the head, a tubular stop 5
slidable on the free end of the flexible mem-
ber and having a slot therein with ears pro-
jecting from the edges of the slot, and an
eccentric pivoted between the ears and
adapted to engage the flexible member.

5. A horse twitch comprising a frame hav-
ing an opening at one end, a rod in screw
threaded relation with the other end of the
10 frame, a flexible member having a noose
passed through the said opening and con-
nected to the said rod; and means for dis-
engaging the rod from the frame to permit
the rod to be slid longitudinally.

15. 6. A horse twitch comprising a frame hav-
ing ears at its ends, the lower ear having
an opening therethrough with screw threads
at the outer end of the opening, a member
20 slidable within the opening in the said ear
and having screw threads coöperating with
the aforesaid screw threads, a screw thread-
ed rod passing through the said screw
threaded portions, means for yieldingly
25 forcing the said member against the rod,
and a flexible member connected to the said
rod and having a noose passing through the
upper ear, whereby when the said member is
disengaged from the rod, the rod may be
freely moved longitudinally.

7. A horse twitch comprising a frame in- 30
cluding end portions, one having an opening
and the other having screw threads, a spring
pressed member movably engaging the lat-
ter portion and having screw threads coöp-
erating with the said screw threads, a screw 35
threaded rod passing through the said screw
threaded portions, and a flexible member
connected to the said rod and having a noose
passing through the said opening, so that
when the said spring pressed member is dis- 40
engaged from the rod, the rod may be freely
moved longitudinally.

8. A horse twitch comprising a frame hav-
ing end portions, one end portion having
an opening, a rod screw-threaded through 45
the other end portion, a head swivelly car-
ried by the inner end of the rod, and a flexi-
ble member attached at one end to the head
and having a noose passed through the said
opening, the other end of the flexible mem- 50
ber being adjustably connected to the head.

In testimony that I claim the foregoing
as my own, I have hereto affixed my signa-
ture in the present of two witnesses.

SEYMOUR FISHER.
